V-TYPE BELT

Eugene E. Brunner, York, Pa., assignor to Read Machinery Co. Inc., York, Pa., a corporation of Pennsylvania

Application July 12, 1943, Serial No. 494,290

3 Claims. (Cl. 74—234)

1

This invention relates to belts used for transmitting power and more particularly to V-type belts.

An object of the invention is to provide an improved V-belt of the type having a plurality of outwardly extending V-shaped ribs formed lengthwise thereof and coextensive the length thereof, the ribs being arranged radially with respect to the main body of the belt and being disposed at an angle less than 180° with respect to each other.

Another object of the invention is to provide an improved V-belt of the above type, in which the longitudinally extending ribs are arranged at an angle of substantially 90° with respect to each other.

Another object of the invention is to provide an improved V-belt of the above type, in which the V-shaped ribs are adapted to engage the grooves of pulleys having vertically disposed and horizontally disposed axes without twisting the belt.

Another object of the invention is to provide an improved V-type belt for operation over cone surfaces of pulleys having their axes arranged at different angular relationships so that the belt is retained from twisting in a predetermined position with respect to the cone surfaces of the pulleys.

With the foregoing and other objects and advantages in view, the invention consists in the preferred construction and arrangement of the several parts which will be hereinafter fully described and claimed.

In the accompanying drawings:

Fig. 1 is a transverse section through one form of V-belt embodying the present invention;

Fig. 2 is an elevation of a portion of the V-belt shown in Fig. 1, looking in the direction of the arrow 2, Fig. 1.

Fig. 3 is an elevation of a portion of the V-belt shown in Fig. 1, looking in the direction of the arrow 3, Fig. 1;

Fig. 4 is a transverse section through another form of V-belt embodying the present invention;

Fig. 5 is an elevation of a portion of the V-belt shown in Fig. 4 looking in the direction of the arrow 5, Fig. 4;

Fig. 6 is an elevation of a portion of the V-belt shown in Fig. 4, looking in the direction of the arrow 6, Fig. 4;

Figs. 7, 8 and 9 are views similar to Figs. 4, 5 and 6, of another type of V-belt embodying the present invention;

Fig. 10 is a transverse section through another

2

form of V-belt embodying the present invention; and

Fig. 11 is an elevation of a portion of the V-belt shown in Fig. 10, looking in the direction of the arrow 11, Fig. 10.

According to the present invention the improved V-type belt 11 is formed of suitable molded material and may have three V-shaped ribs 12, 13 and 14, as shown in Fig. 1, two V-shaped ribs 15 and 16, as shown in Figs. 4 and 7, or four V-shaped ribs 17, 18, 19 and 20, as shown in Fig. 10.

All of the above referred to V-shaped ribs are formed lengthwise of the belt and extend radially from the main body portion 11. These ribs are arranged at right angles or 90° with respect to each other, and the ribs 12, 13 and 14 of the belt shown in Fig. 1 should preferably all correspond in cross sectional dimensions. Similarly the ribs 14 and 15 of the belt shown in Fig. 4 should both preferably correspond in cross sectional dimensions, and likewise the ribs 14 and 15 of the belt shown in Fig. 7 should both correspond in cross sectional dimensions. The four ribs 17, 18, 19 and 20 of the form of belt shown in Fig. 10 also should all correspond in cross sectional dimensions.

In order to limit to a minimum the amount of stretching of the material used in constructing the belt 11, a cable or similar element 21, can be embedded lengthwise within the main body of the molded material, as shown in Figs. 1, 4, 7 and 10, respectively.

With a V-type belt of the form shown in Fig. 1 in which the belt is formed with three V-shaped ribs 12, 13 and 14, it is possible to train the belt over the cone surfaces or grooves of sheaves so that the belt, in travelling around the sheaves, will remain at all times in the same position without any tendency for the belt to twist or turn out of such position.

Thus, as shown in Fig. 1 the rib 12 of the belt may ride in the V-shaped groove of a pulley or sheave 22 having a horizontal axis of rotation,

the rib 13 may ride in the V-shaped groove of a pulley or sheave 23 having a vertical axis of rotation, and the rib 14 may ride in the V-shaped groove of a pulley or sheave 24 having a horizontal axis of rotation.

As shown in Fig. 1, the arrangement of the pulley or sheave 24 with respect to the belt is such that the belt is supported by sheave 24 in a horizontal flight. At the end of such horizontal flight either a pulley or sheave 23 or a pulley or sheave 22 can be utilized to guide the belt in a flight of a

direction different from the flight of the belt past the pulley or sheave 24. Thus, if it is desired that the flight of the belt should be in a direction towards the left, then the belt is trained through the V-shaped groove of pulley or sheave 23. On the other hand, if it is desired that the flight of the belt should be upwardly from the horizontal flight over pulley or sheave 24, then the belt is trained through the V-shaped groove of pulley or sheave 23. By constructing the belt with the series of ribs 12, 13 and 14 and by arranging the pulleys or sheaves 22, 23 and 24, respectively, in the manner heretofore referred to, the belt will be guided by the sheaves in a number of directions without any tendency for twists being formed in the belt. In other words, assuming that the belt of Fig. 1 is endless and passes over a series of sheaves arranged with horizontal and vertical axes of rotation, the belt will make a complete circuit around all of the sheaves with the two ribs 12 and 14 always vertically disposed, in the manner shown in Fig. 1, and with the rib 13 always horizontally disposed.

The form of V-belt shown in Fig. 1 may have a portion 26 formed on the main body thereof opposite to the rib 13. This portion 26 provides means by which a flight or some such element (not shown) can be secured to the body of the belt when desired.

The only difference in the two belts shown in Figs. 4 and 7, respectively, is in the configuration of the main body of each belt.

In the form shown in Fig. 4 the two ribs 15, 16 project outwardly from the main body of the belt and the main body has two surfaces 31 and 32 arranged at right angles to each other on the opposite sides of the body from the ribs, respectively. Thus, surface 31 is arranged perpendicular to the longitudinal center line through rib 15 and surface 32 is perpendicular to the longitudinal center line through rib 16. This construction provides a heavy main body portion for the belt, useful when the belt is arranged to transmit considerable power.

On the other hand, in the form of V-belt shown in Fig. 7, the cross sectional area of the belt is somewhat less than the cross sectional area of the form of belt shown in Fig. 4. This is accomplished by forming the body with an angular surface 33, which surface is arranged at an angle of substantially 45° with respect to the longitudinal center lines of the ribs 15, 16, respectively.

In both forms of belts shown in Figs. 4 and 7, the ribs 15 are adapted to engage the cone surfaces of pulleys or sheaves 34, having vertical axes of rotation, and the ribs 16 are adapted to engage the cone surfaces of pulleys or sheaves 35, having horizontal axes of rotation. With the belt trained or guided by the pulleys or sheaves 34, 35, no twisting will take place and the two ribs 15, 16, will always remain in the position shown.

The form of V-belt shown in Fig. 10 is particularly adapted to be used with sheaves or pulleys arranged so that the flight of the belt can extend through a series of horizontal and vertical paths without twisting or turning out of a predetermined position. The fourth V-shaped rib 20 and the sheave 40 with vertically disposed

axis of rotation enables the belt to be guided in a direction towards the right in addition to the several directions of travel which may be imparted to the belt with the form shown in Fig. 1.

While I have described the invention in great detail and with respect to the present preferred form thereof, it is not desired to be limited thereto since changes and modifications may be made therein without departing from the spirit and scope of the invention. The invention may be embodied in other specific forms without departing from the essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

Having thus described my invention what I claim is:

1. A V belt of the type described comprising a plurality of radially extending V-shaped ribs formed lengthwise thereof and coextensive the length thereof, all of said ribs being substantially similar in form and size and being arranged at an angle of approximately 90° with respect to each other, each of said ribs having three walls, including two inclined side walls and an outer end wall, the adjacent side walls of adjacent ribs forming a reentrant angle, the two side walls of each rib being inclined at substantially similar angles with respect to the radial center line of the rib and the outer end wall of each rib being arranged substantially at right angles to the radial center line of the rib.

2. A V belt of the type described comprising a body having three radially extending V-shaped ribs formed lengthwise thereof and coextensive the length thereof, all of said ribs being substantially similar in form and size and being arranged with the longitudinal center lines of each at an angle of approximately 90 degrees with respect to each other, each of said ribs having three walls, including two inclined side walls and an outer end wall, the adjacent side walls of adjacent ribs forming a reentrant angle, the two side walls of each rib being inclined at substantially similar angles with respect to the radial center line of the rib and the outer end wall of each rib being arranged substantially at right angles to the radial center line of the rib.

3. A belt comprising a plurality of radially extending V-shaped ribs formed lengthwise thereof and co-extensive the length thereof, an adjacent pair of ribs being arranged with their radial center lines disposed at an angle less than 180° with respect to each other, said ribs each including side walls inclined at substantially similar angles with respect to the center line of the rib, adjacent side walls of adjacent ribs being angularly disposed with respect to each other, to form a reentrant angle greater than the angle between the radial center lines of said adjacent ribs.

EUGENE E. BRUNNER.
